DESIGN FOR A BRAID

Hans Albert Philips, Stratford, Conn., assignor to
The American Fabrics Company, Bridgeport,
Conn., a corporation of Connecticut

Application June 30, 1938, Serial No. 78,168

Term of patent 7 years

To all whom it may concern:

Be it known that I, Hans Albert Philips, a citizen of the United States, residing at Stratford, county of Fairfield, and State of Connecticut, have invented a new, original, and ornamental Design for Braid, of which the following is a specification, reference being had to the accompanying drawing, forming part thereof.

The figure is a plan view of a piece of braid, showing my new design.

I claim:

The ornamental design for a braid, substantially as shown.

HANS ALBERT PHILIPS.
